UNITED STATES PATENT OFFICE

163,029

TABLE OR SIMILAR ARTICLE

Lennart G. Erickson and Charlotte Erickson,
Hillsborough, Calif.

Application June 10, 1950, Serial No. 10,447

Term of patent 14 years

(Cl. D33—14)

To all whom it may concern:

Be it known that we, Lennart G. Erickson and Charlotte Erickson, each a citizen of the United States of America, and each a resident of the city of Hillsborough, county of San Mateo, State of California, have invented a new, original, and ornamental Design for Table or Similar Article, of which the following is a specification, reference being had to the accompanying drawing, forming a part thereof.

In the drawing:

Fig. 1 is a top plan view of a table or similar article, showing the new design;

Fig. 2 is a side elevational view;

Fig. 3 is an end elevational view thereof; and
Fig. 4 is a view in bottom plan.

We claim:

The ornamental design for a table or similar article, substantially as shown.

LENNART G. ERICKSON.
CHARLOTTE ERICKSON.
